See application file for complete search history.

FIG. 1 is a top, front, left side perspective view of a belt with pouch showing our new design;

FIG. 2 is a top plan view thereof;

FIG. 3 is a front elevation view thereof;

FIG. 4 is a bottom plan view thereof;

FIG. 5 is a rear elevation view thereof;

FIG. 6 is a left side elevation view thereof; and,

FIG. 7 is a right side elevation view thereof.

The broken lines represent portions of the belt with pouch that form no part of the claimed design. The pairs of brackets adjacent wavy break lines form no part of the claimed design and indicate that the appearance of any portion of the article between the break lines forms no part of the claimed design.
